Specification of Letters Patent.

Patented July 21, 1914.

Application filed June 2, 1908. Serial No. 436,215.

To all whom it may concern:

Be it known that I, CHARLES PEASE, a citizen of the United States, residing at Beverly, in the county of Essex and Commonwealth of Massachusetts, have invented certain Improvements in Splitting or Skiving Machines, of which the following description, in connection with the accompanying drawings, is a specification, like reference characters on the drawings indicating like parts in the several figures.

This invention relates to improvements in machines for treating stock, and is of especial utility when embodied in apparatus for splitting or skiving thin pieces of leather, felt or similar material in a direction substantially parallel to the surface thereof, although I contemplate the use of my improvements in any field for which they are adapted by their nature.

One object of my invention is to provide a machine which shall skive very thin, soft or flimsy stock evenly and with high efficiency, and for this reason I prefer to make use of a machine of the type provided with a working member or knife which is non-continuous and treats recurrently the stock as the latter is fed by any suitable means, the arrangement preferably being such that the work treating member or knife is caused to traverse operatively the forward edge of the stock, to produce a drawing cut. This drawing cut cannot be produced with the stationary knife often used in machines for this purpose, while in similar machines employing a band knife the knife is passed over very large rolls, and great power is applied to keep this band taut, so that machines employing a band knife must be constructed very large and heavy, thereby greatly increasing their cost, and the floor space taken up by them, and making it impossible for the small manufacturer to afford to employ them.

The working device in my improved machine may conveniently comprise a plurality of knives, knife blades or other suitable cutting devices, connected in series at their rear ends by links of improved form in the particular embodiment of this invention which is illustrated in the drawings and herein-after described, to form an endless chain, preferably operating throughout its length in the plane of the stock, and arranged to carry the knives along near the bite of a

pair of feed rolls through which the forward edge of the leather, felt or similar stock is advanced and presented for the recurrent action of the knives, the forward cutting edges of the latter serving together as a unitary cutting tool, during forward movement of the chain, to engage the leather continuously as it is fed through the rolls, and split the leather with a drawing cut. When the individual blades of such a chain knife approach the active portion of the operative path of the working device, the free ends of the knives separate at their working peripheries as they swing around the curved end of the path into the working tangent thereof, and it is desirable that the part of the knife brought first into operative engagement with the leather or other work at its lateral boundary should be of a cutting contour, so that cutting action will begin at the instant of contact, to avoid tearing, crumpling, or otherwise marring the flimsy leather or other work.

Accordingly, an important object of my invention consists in providing the individual knives with forward cutting edges which at each side merge into slightly rounded cutting corners; and another important object of my invention is to provide means for dressing the knives by grinding or otherwise sharpening or treating these cutting edges and corners uniformly and frequently and without interfering with the active operation of the machine, the dressing action preferably being carried on upon the knives while in motion idly through an inactive region of the operative path of the working device.

As the ordinary chain link is not well fitted to sustain knife blades working in the plane of the chain, another important object of my invention is to provide a chain composed of links especially devised to carry the knives, and arranged to engage with actuating sprocket wheels in such a manner that the knives will be carried rigidly and in radial position around the curved portion of their operative path adjacent to the sprocket wheels, to insure firm cutting engagement with the lateral boundary of the leather or other work.

An additional feature of the improved link is the means which I have provided for mounting the knives on their respective links in such fashion as to insure rigid op-

erative engagement of the knife with the work, while permitting independent individual adjustment of the knives to and from the work.

5 Among other important objects of my invention are included a working table adjustable toward and away from the bite of the feed rolls; an apron adjustable angularly with respect thereto; and means to maintain 10 the cutting edges of the knives firmly in engagement with the dressing device.

The various features of my invention will be illustrated and described fully in the accompanying drawings and specification and 15 pointed out in the claims.

Figure 1 is a view in rear elevation of a leather-splitting machine in the construction of which my improvements have been embodied; Fig. 1^a being a detail view in plan, 20 on a smaller scale, of the work-apron taken separately; and Fig. 1^b a similar view of the under side of the work-apron; Fig. 2 is a plan view of said machine upon an enlarged scale, the work-apron being omitted 25 to reveal the chain knife and its operating mechanism; and parts being shown in section; Fig. 3 is a fragmentary, detail view, similar to Fig. 2; with the chain knife omitted, showing the means for adjusting the 30 chain-driving mechanism and guides; Fig. 4 is fragmentary detail view in plan, on an enlarged scale, of three of the knife mounts, or links, connected, but the knives being omitted. Fig. 5 is a fragmentary view in 35 transverse vertical section, taken on the line x^5-x^5 , Fig. 2, showing adjacent portions of the feed-rolls, worktable and work-apron, with one of the knife blades and its mount shown in place; Fig. 6 is a detail view in 40 side elevation, partly in section, looking from right to left, Fig. 1, of the mechanism for dressing the rounded corners of the cutting edges of the knives; Fig. 7 is a view in rear elevation, partly in section, showing 45 the mechanism for dressing the straight cutting edges of the blades. Fig. 8 is a fragmentary detail view on a larger scale in vertical, transverse section on the line x^8-x^8 , Fig. 1^b, of a portion of the knife dressing 50 mechanism; and one of the dressing tools being shown in elevation. Fig. 9 is a fragmentary detail view in rear elevation, partly in section, on a smaller scale, of the mechanism for adjusting the lower feed roll; while 55 Fig. 10 is a view in side elevation of the machine, looking from left to right, Fig. 1.

The machine as shown comprises end standards 2 supporting an actuating shaft 4 which is driven by power applied thereto 60 in any ordinary manner. The end standards 2 also support an upper feeding and gage roll 6 mounted on shaft 10, said shaft being driven by gear wheel 14 which is mounted thereon and engages with a gear wheel 65 mounted on shaft 4 through the medium of

an intermediate pinion 16. End standards 2 also support a lower feeding roll 8, mounted on shaft 12, said shaft being driven by a gear wheel 18 which is mounted thereon and engages a gear wheel 20 mounted on 70 shaft 4.

The feed roll 6 is mounted so as to be adjustable in any well-known or suitable manner, as, for instance, through the medium of cams 22 mounted at each end of a shaft 24 supported on the end standards 2 of the machine and adapted to be turned by a hand wheel 26, said cams engaging the heads 28 of adjustable screws mounted in blocks 30 which are slidable in the ways 32 formed 80 in the end standards 2 of the machine. Said blocks 30 serve as bearings for shaft 10 and are pressed upward as by springs 31 to a position determined by the contact of cams 22 and the heads of adjustable screws 28. 85 By turning shaft 24 by means of the hand wheel 26 the position of blocks 30 will be adjusted by means of cam 22 and screw 28 and the position of feed roll 6 raised or lowered accordingly. 90

The bearing blocks 29 for the shaft 12 on which feeding roll 8 is mounted are also slidable in the ways 32 and any suitable means may be provided to adjust the roll 8 relatively to the roll 6, and to displace it 95 to permit the insertion of the leather or other stock, and thereafter to return the roll 8 to feeding position. One convenient form of such means is illustrated in Fig. 9, where the blocks 29 of the feed roll are 100 shown as connected pivotally to the members 33 of toggle levers, the arms 34 of which are mounted pivotally on adjustable bearing blocks 35 in ways 36 at the bottom of the standards 2, set screws 37 with retaining nuts 38 being provided to regulate the position of these lower bearing blocks. Similar set screws 39 with retaining nuts 40 are provided to limit the upward thrust of 105 the toggles so that the lower feed roll will not be forced too close to the upper roll after the adjustment has once been made. 110

In order to accomplish quick retraction of the lower roll from the upper roll, and approach of the two, as desired, I have 115 shown arms 41, 42 connected pivotally at 43, 44 with the elbows of the toggles respectively, these arm members entering a sleeve member 45 containing a spring 46 which tends to force the members apart normally and thereby to hold the lower feed roll yielding up to its work. The normal position of the roll can be regulated by turning hand wheel 47 upon threaded portion 48 of the member 41, as will be readily understood upon inspection of Fig. 9, rotation of the top of the wheel toward the observer serving to thrust the roll upward, and vice versa, within the limits determined by the set screws 39. At any time by rota- 120 125 130

tion of the bottom of the hand wheel quickly toward the operator, the feed roll 8 will be permitted to drop, so that the material will be left free for adjustment between the feed rolls, after which by rotating the top of the hand wheel quickly toward the observer the roll will be returned to its adjusted position, the set screws 39 preventing it from being forced past the predetermined position of adjustment.

The parts heretofore described form part of a machine well known in the art as the "Stowe Splitter" and may be varied as found desirable in carrying my invention into practice.

Before proceeding with a detailed description of my improvements, I will first call attention briefly in summary to the principal operating parts of the machine illustrated as a preferred embodiment, as follows:

The sheet of leather, or other material to be treated, as it is fed between the rolls 6 and 8, (see Fig. 5) is engaged operatively at once upon emergence from the rolls and is subjected to the continuous splitting action of a chain-knife composed of a plurality of knife blades 49, these knives moving toward the observer in Fig. 5 and toward the left hand in Fig. 2, each knife entering into cutting engagement with the lateral boundary of the forward edge of the work as each knife passes from the position occupied by the knife bearing the reference numeral 48 to the position numbered 49, occupied by the knives respectively moving along the tangent, and after leaving the tangent and moving toward the position occupied by the knife bearing the numeral 50 and thence to 51, the knives successively continue in cutting engagement with the material as long as they contact therewith; this being achieved from 50 to 51 by the slightly rounded cutting corners which in accordance with my invention, are preferably provided at the extremities of each beveled cutting edge. Passing from the point 50 around an actuating sprocket wheel at the left of Fig. 2, first to the position occupied by the knife bearing the numeral 51, thence to that numbered 52 and on to number 53, the knives are subjected to the action of the sharpening grinder or other form of dressing tool or tools 54 and 55 which dress first the forward and then the rearward rounded corners 56 and 57 upon each knife. The knives then pass on to the idle return tangent in which the several knives bear the numeral 58, when they are subjected respectively to the action of the dressing tools 59, 60, which serve to dress the lower and upper edges of the transverse forward cutting edge of each knife successively; and from that point the knives pass in series to and around the right hand sprocket wheel into reengagement with the material to be treated, and the cycle of operations already described recurs continuously, the work-treating and dressing proceeding concurrently with feeding of the stock without interruption in the operation of the machine.

In accordance with my invention, and as already set forth briefly, the working device may, and preferably will, be constructed approximately as illustrated, comprising a series of blades or knives 48, 49, 50, etc., connected suitably at or near their rear ends as by link members 61 to form an endless chain knife preferably operated throughout its length in a plane approximately at right angles to the vertical plane passing through the axes and bite of the feed rolls, and preferably tangent to said plane at the line of operative engagement with the work. Each of these knives has at its outer or free end, as already noted, a cutting edge, preferably ground above and below to a bevel which may be of any suitable contour, and is herein shown as straight, and in accordance with my invention the cutting edge in its preferred form is formed transversely to the length of the blade and terminates in round cutting corners 56 and 57 similarly ground above and below. Each knife is carried preferably (see Figs. 2 and 5) by a separate link or mount 61, these links being articulated to form a chain, the connection being established in any suitable fashion, as by pins 62 (see Fig. 4) passing through lugs 63 at one side of each link, which lugs embrace a lug 64 on the adjoining link; suitable means being provided, in accordance with my invention, to insure a rigid union between the blade and its mouth. One such convenient union is illustrated in the form of a channel flanked by upward projections 65, between which lies an extension or tail piece 66 of the blade, and this shank, extension or tail-piece may be secured in any suitable manner to the mount, as by a cap-screw 67 passing through an elongated slot 68, with a washer if found desirable for the sake of stability. Such a connection permits ready adjustment of each knife independently of the others, to bring the cutting edge of each blade into alinement with the tangent working line at the bite of the rolls.

Each of the links preferably has at its rear a medial recess 69 (see Fig. 4) to receive a tooth of the sprocket wheels 95, 96, the rearwardly extending portions 70 embracing the tooth, so that the link and knife become for the time being a radial extension of the tooth, and the knife is therefore carried rigidly into operative contact with the lateral boundary of the leather or other work, an important object of my invention, as already noted, and one which can be served with especially satisfactory results by my novel form of link, although I do not

limit myself to this specific mount, having devised the same to obviate the deficiencies of existing forms of links, which lack the construction necessary to rigid, radial support, the ordinary link being engaged by the sprocket tooth usually at a region near one end of the link, either inside or outside the same.

A table, or other suitable support, 71, will preferably be provided for the chain knife, and may be cut away as at 72 (see Figs. 5 and 3) to furnish a track for the links, having also a rabbet or shoulder 73 over which extends and travels the overhanging head 74 of each link, (see Fig. 5) while beyond this shoulder, the projecting rim 75 of the table serves as a support for the knife blades 49 each of which extends between the rolls in such position that the beveled under surface of its cutting edge affords clearance for the under strip cut from the material, said under strip passing forward and downward in the curved space 76 between the periphery of the lower feed roll and the under-cut rim of the table.

To hold the knives up to their work, I have shown at 77 an abutment in engagement with the rearward portions 70 of the respective links, this abutment being preferably adjustable and provided with slots 78 (see Fig. 2) to receive binding screws 79 tapped into the table 71. Additional thrust screws 80 may also be provided, for the abutment, these working in lugs 81 extending upward from the table. The table as a whole may be arranged, as shown, to move bodily toward and away from the feed rolls, sliding on a base 82, and actuated by screws 83 each screwed into the base 82, and engaging an overhanging lip 85 on the table with a collar 86 (see Fig. 1).

Above the table 71, and resting thereon, I have shown a removable and adjustable apron 87 having its forward edge beveled as at 88 (see Figs. 1^a and 5) and provided with a movable portion 89, having binding screws 90 to hold its forward edge down toward the abutment and blades, while its rear may be tilted upward by set screws 91, acting upon an abutment 92 which serves as a guide for the links along their idle tangent, this abutment having slots 93 and binding screws 94, to permit its fixation in adjusted position. The free edge of the upper layer 55 of leather, after having been split, will ride up over the knife upon the forward edge of the apron, and back over the apron, the latter serving to prevent the laterally moving knives or their cap screws or other moving parts from catching or tearing the upper layer of the leather.

As one convenient form of means to actuate the chain knife, I have shown sprocket wheels 95, 96, secured by cap screws 97 and washers 98 upon the heads of vertical shafts

99, 100, of which the former is preferably journaled (see Fig. 2) in fixed position in the table, having a bevel gear 102 meshing with bevel gear 103 upon a horizontal shaft 104 which shaft is provided with a central sprocket hub 105 (see Fig. 2) operated by a chain 106 running to a shaft 107 (see Fig. 1) journaled between the standards 2 and actuated in turn by the main shaft 4 through the medium of a sprocket chain 108. An idler 109 may be provided, if desired, at the end of a swinging arm 110 to take up the slack in the chain 106. I prefer to mount the vertical shaft 100 in a journal block 112 (see Fig. 3) movable in an elongated slot 113 in the work table 71, a screw bolt 114 serving to move the bearing block to take up any slack in the chain-knife, this bolt working in a bridge 115 secured removably to the table 71 by screws 116. The horizontal shaft 104 is preferably movable axially in the hub 117 of the bevel gear 103, being connected rotatively therewith by suitable means, as for example, the spline 118, (see Fig. 1) in order to permit the bevel gear 119, fixed at the other end of the horizontal shaft 104 to rest in constant engagement with, and to actuate, a bevel gear 120 upon the lower end of the vertical shaft 100 as the latter shifts when adjusted.

When the chain knife is actuated by the sprocket wheels to move along the working tangent at the bite of the feed rolls, the blades passing the tangent at any given time form substantially a unitary and straight cutting edge, although they may be slightly separated, but at the respective ends of the cutting tangent the cutting engagement takes place, in the instance illustrated, in a curved arc of a radius equal to the distance from the center of the sprocket wheel to the cutting corner of the knife edge, and when the knives have cleared the material, their cutting edges will be separated considerably from each other as they pass around the sprocket wheel, and until they approach one another again to traverse the idle tangent upon their return journey toward the working tangent. I avail of this separation of the knives in the preferred embodiment of my invention illustrated to dress the round corners 56, 57 (see Fig. 2) and any suitable means may be adopted to accomplish this dressing operation.

As one convenient form of dressing mechanism, which is of especial utility for the type of machine herein illustrated for the reason that the dressing operation can, and should be, carried on while the working device is in active operation and without interfering with its operation, I have devised an improved mechanism for dressing tools of the class described, comprising a plurality of rotating sharpening disks which serve respectively to grind the upper and

lower surfaces of the beveled cutting edges simultaneously and symmetrically. The preferred form of this mechanism is shown best in Figs. 1, 2, 6 and 10, wherein the reference numerals 54 and 55 designate respectively the disks of the dresser devices, whose dressing surfaces 121 and 122 may be composed of emery, adamite, carborundum or other suitable material, abrasive or otherwise.

Any suitable means may be utilized to present these devices in proper relation with the knives as they successively pass the dressing points, and in the instance illustrated the support for these dressing devices takes the form of an L-shaped bracket 123 secured upon the base by a bolt 124 (see Fig. 1) passing through a slot 125 in the foot of the bracket, which is provided with 15 turntables 126 and 127 (see Figs. 2 and 6) for the upper and lower disks respectively, these turntables having horizontal pivot bolts 128 with nuts 129 to secure them in adjusted position rotatively, and additional 20 means for such adjustment being provided in the set screws 130 which pass through threaded holes 131 in lugs 132 of the bracket, engaging radially projecting sleeve members 133. The sleeve members may be 25 split to receive bearing bushings 134 through which pass the spindles or shafts 135 and 136 for the dressing disks respectively, and similar bearing sleeves 137 and 138, with bushings 139 may be provided at the opposite 30 sides of the turntables to afford broad bearings for the shafts. Each of these split bearing sleeves may have screw bolts 140 to tighten them and retain the bushings in place, and I have shown at 141 a spring 35 within a tube 142 and bearing against the rear of plungers 143 passing through apertures in the bracket lugs 144, this spring serving through the medium of the plungers to separate the disks to receive, and act 40 properly on, the beveled corners of the knives. When adjusted as shown, the dressing disks will produce a slightly concave bevel on the upper and lower surfaces of the cutting edges of the corners, but they 45 may be arranged to produce a straight bevel. The shafts 135 and 136 may be provided respectively with pulleys 145 and 146, traversed and actuated by a driving belt 147 (see Figs. 1 and 2) running to a pulley 148 50 on a shaft 149 carried by the end standards 2 and having at its outer end a pulley 150 driven by a belt 151 which runs to an intermediate pulley 152 belted to the driving pulley 153 on the shaft 4. The pulley 154 55 on the shaft 135 (see Fig. 6) may be loose, the pulleys 145 and 146 being shown as fixed to their shafts by screws 155.

From the above description, it will be understood that the dressing disks 54 and 55 60 can be adjusted bodily with their bracket

toward and away from the line of travel of the cutting corners of the knives after loosening the bolt 124, (see Fig. 1); the individual disks can be adjusted axially in the sleeve bearings 133, etc. at right angles to 70 the first mentioned adjustment, to regulate the curvature of the cutting corners; and the disks can be adjusted, by rotation of the turntables, to dress more or less deeply. As the knives reach respectively a position intermediate that occupied by the knife bearing the reference numeral 51 and that bearing the number 52, the dressing disks 54 and 55 will dress the forward rounded cutting corner 56 of the knife; and the rear rounded corner 57 of the knife will be dressed thereby as the blade passes on to the position numbered 53.

The blades respectively have their longer cutting edges dressed by the action of the surfaces 156 and 157 of disks 59 and 60 (see Figs. 1, 2 and 7) these being supported in any suitable fashion, as upon shafts 158 and 159 carried by the bearing head 160, having a stud or rock shaft 161 passing through, and rotatable in, a bearing lug 162 secured to the under surface of the table 71 by screws 163, a set screw 164 serving to hold the rock shaft and head in adjusted angular position, with one of the disks 59 below the 85 plane of the knives in position to engage and dress their under surfaces in succession, while the other disk 60 occupies a similar position relatively to the upper surfaces and edges of the knives. I have shown the table 90 as cut away at 165 to receive the lower disk and give the same access to the under surfaces of the blades, and in Fig. 8 I illustrate a spring gib or presser device 166 which may be provided to hold each blade in dressing 95 engagement with the lower dresser disk, this presser device being mounted, as shown in Figs. 1^b and 8, within an undercut recess 167 toward the rear 168 of the apron 87, a spring 169 co-operating therewith to force 100 each blade 58 into dressing engagement with the disk as the blade comes into operative 105 engagement with the presser device.

In Fig. 7 I have shown means for adjusting the shafts 158 and 159 of the straight edge dresser devices axially, independently of each other, and these means may take any suitable form; one such convenient form being illustrated in the externally threaded rotating bearing pieces or bushings 170 and 115 171 passing through threaded apertures 172 in split arms 173, which are shown as provided with tightening screws 174 by which the bearing pieces may be secured after they 120 have been adjusted by means of the milled heads 175. Rotation of one of the heads causes axial displacement of its bushing and shaft toward or away from the plane of the working device, the shafts being provided at 125 or near one end with collars 176, fastened by 130

- set screws 177, and being provided with pulleys 178, fastened by set screws 179 through their hubs on the opposite side of the bearing pieces 170 and 171, so that the shafts move co-axially with the bearing-pieces, but are free to rotate in the bearing bores 180 therein. A driving belt 181 connects the pulleys 178 for co-rotation at approximately the same speed, and toward each other peripherally, and a bracket 182 will preferably be provided, with direction pulleys 183 (see Fig. 1) over which the belt 181 runs to a pulley 184 on the shaft 149. After the blades have been dressed, in order to afford opportunity for their inspection before they pass around the sprocket wheel 95 to the working tangent, I have shown the table as cut away at 185, at the end of the idle tangent, (see Fig. 2).
- Having illustrated and described my invention thus fully, and suitable means for carrying the same into effect, it will be understood that I do not limit myself to the specific mechanism herein shown and described, nor in general otherwise than as set forth in the claims, read in connection with this specification.
- What I claim and desire to secure by Letters Patent is:—
1. In a machine of the class described provided with a chain-knife comprising a series of blades each having a transverse cutting edge and rounded cutting corners, and means for actuating said knife, means acting upon said knife while in motion for dressing said straight edges, and separate means acting similarly for dressing said rounded corners.
2. In a machine of the class described; provided with a chain-knife comprising a plurality of blades, each provided with a transverse cutting edge and rounded cutting corners, means operating during the movement of the knife to dress said rounded corners.
3. Dressing mechanism for apparatus of the class described, said apparatus having an articulated knife comprising a plurality of separately formed cutting members with transverse cutting edges having rounded cutting corners, and said dressing mechanism comprising a disk held in position to engage and adapted to dress said rounded corners respectively, substantially as described.
4. The combination with an endless chain-knife and its table, said knife comprising a plurality of link members each including a knife and its mount; of a plurality of abut-

ment tracks traversed by said link members respectively and each adjustable to vary the line of travel of a plurality of said links at the same time; abutment screws and clamping screws to hold said abutments in adjusted position; and means to permit adjustment of said knives independently upon their mounts without varying the position of said abutment.

5. In a machine for treating material of the class described; a chain knife; a plurality of actuating sprocket wheels therefor; said knife and wheels lying respectively in the plane of feed of said material; said sprocket wheels being mounted on shafts provided with gears; and a countershaft geared to said wheel shaft gears to actuate the same; and means to take up the slack in said chain, said means permitting said gears to remain in mesh.

6. In a machine of the class described, the combination with a chain-knife and its table; of an apron covering a portion of said chain-knife and having its forward edge beveled to engage the material after treatment and sustain it above said knife; said table having a tiltable portion, means to secure said apron bodily to said table; and means to adjust the angular relation of said tiltable portion of said apron to said table.

7. In a machine for treating material of the class described; a chain-knife; a plurality of actuating sprocket wheels therefor; said knife and wheels lying respectively in the plane of feed of said material; said sprocket wheels being mounted on shafts provided with gears; and a counter shaft geared to said wheel shaft gears, and to actuate the same.

8. A link for chains of the class described; said link comprising a mount portion grooved to receive and support a working device, and presenting rearwardly a recess extending along the medial line of said working device to receive a suitable actuating device; said rearwardly extending recess and groove being co-extensive and in communication for a portion of their length; substantially as described.

In testimony whereof I have signed my name to this specification in the presence of two subscribing witnesses.

CHARLES PEASE.
